United States Patent Office

Des. 202,544
Patented Oct. 19, 1965

202,544

HINGE

James W. Maize, Fullerton, Calif., assignor to Hyer Hardware Mfg. Co., Anaheim, Calif., a corporation of California

Filed Feb. 2, 1965, Ser. No. 83,656

Term of patent 14 years

(Cl. D10—9)

FIG. 1.

FIG. 2.

FIG. 3.

FIG. 1 is a front elevation of a hinge showing my new design;

FIG. 2 is a side elevation thereof, and

FIG. 3 is an end elevation thereof.

The dominant features of the design reside in the portions shown in full lines.

I claim:

The ornamental design for a hinge, as shown and described.
